DESIGN FOR A PENCIL SHARPENER

George J. Staab, Springfield, N. J.

Application June 15, 1946, Serial No. 130,753

Term of patent 7 years

(Cl. D74—1)

To all whom it may concern:

Be it known that I, George J. Staab, a citizen of the United States of America and a resident of Springfield, in the county of Union and State of New Jersey, have invented a new, original, and ornamental Design for a Pencil Sharpener, of which the following is a specification, reference being had to the accompanying drawing, forming a part thereof.

Figure 1 is a perspective view of a pencil sharpener, showing my new design, viewing it from the front and top; and

Figure 2 is a similar view observing the pencil sharpener from the rear and bottom.

My design for a pencil sharpener is characterized specifically by the continuous arrangement of the flutes on the concave portions of two sides and the bottom wall, all as illustrated.

I claim:

The ornamental design for a pencil sharpener, as shown and described.

GEORGE J. STAAB.
